UNITED STATES PATENT OFFICE.

GEORGE W. HOLLIS, OF BOSTON, MASSACHUSETTS, ASSIGNOR TO SWIFT AND COMPANY, OF CHICAGO, ILLINOIS, A CORPORATION.

DRYING APPARATUS FOR HIDES, &c.

No. 841,866.

Specification of Letters Patent.

Patented Jan. 22, 1907.

Application filed May 23, 1906. Serial No. 318,329.

To all whom it may concern:

Be it known that I, GEORGE W. HOLLIS, a citizen of the United States, residing in Boston, in the county of Suffolk and State of Massachusetts, have invented an Improvement in Drying Apparatus for Hides, Skins, and Leather, of which the following description, in connection with the accompanying drawings, is a specification, like characters on the drawings representing like parts.

This invention relates to a drying apparatus especially adapted for use in tanneries for drying hides, skins, and leather, and particularly for drying leather having a coating of material which requires exposure to the sun, such as patent or enamel leather.

As now commonly practiced and known to me hides or skins which are converted into patent and enamel leather are tacked or otherwise secured to suitable frames and have applied to them a plurality of coats of the composition or material which forms the patent surface or enamel, and each coat of material is allowed to dry in the air, each coat after the first coat being exposed to the sun to obtain the drying action required for producing successful patent or enamel leather.

As now commonly practiced each frame, with a skin thereon, is taken by a workman after each coat of the composition or material is painted or applied thereon and carried out into the yard, where it is placed against a fence or other suitable support and exposed to the air and sun's rays until dried. This method of drying requires considerable handling of the frames, is slow, laborious, and expensive. So, also, in case of showers arising after the frames have been placed in the yard the workmen are obliged to carry each frame back into the building before the skin has been dried and again carry it out into the yard after the shower, which adds additional labor to the workman and expense to the tanner.

The present invention has for its object to provide apparatus with which the hides, skins, or leather can be dried in a substantially continuous manner with the least possible labor on the part of the workman and at minimum expense to the tanner. For this purpose a support or runway is employed which in practice will extend from a building out into an open space or yard, and pro-

vision is made for supporting the skin-carrying frames on the runway or support in such manner as to enable the frames to be placed thereon and automatically carried out of the building in which the coating material is applied and into the sunlight. Provision is made for inclining the frames so that the painted or coated skin may be effectively presented to the action of the sun's rays. The frames may thus be conveyed in a minimum time so as to expose the skins thereon to the sunlight and air and to again place them under cover, either when properly dried or to avoid being damaged by rain.

These and other features of this invention will be pointed out in the claims at the end of this specification.

Figure 1 shows in perspective a sufficient portion of an apparatus embodying this invention to enable it to be understood; and Fig. 2, a section, on an enlarged scale, on the line 2 2, Fig. 1, looking toward the left.

In the present instance one form of apparatus embodying this invention is shown, which consists of a support in the form of a rail *a*, which rests upon and is suitably secured to an elevated structure comprising, as herein shown, cross bars or ties *b* and upright posts *c*, which latter may be set in the ground or be otherwise supported on a suitable base. The support or rail *a* has coöperating with it a plurality of skin-supporting frames *d*, which may be of any suitable or usual construction, such as now commonly used in tanneries for drying hides, skins, and leather, and which in the present instance are provided at their upper end with trolley or grooved wheels *e*, which are mounted to turn on suitable pins or shafts *f*, secured to the top pieces of the said frames. Each frame *d* may and preferably will be provided with a plurality of wheels *e*, which are located below the upper edge of the top piece of the frame and between the side pieces of the same, so as not to interfere with the ordinary uses of the frame—as, for instance, so as to permit the frame with the skin *h* thereon to be placed in the usual baking-ovens, (not shown, but which are now employed in the manufacture of patent and enameled leather.) The skin *h* may be secured to the frame *d* in the usual manner, and, as shown, said skin is secured to the frame by cords *j*. The elevated support or

rail *a* may and preferably will be inclined downward from the starting-point to the end, so that the frames *d* with the skins thereon may be automatically conveyed by gravity from the place or building where the first coating is applied to the place or building where the final step in making the enameled or patent leather is carried on. The rail *a* is located at one side of the upright posts *c*, so that under normal conditions the frames *d* may hang vertically while traveling from one position to another, and in order to prevent the frames being arrested in their movement or travel by striking the supporting-posts under the influence of the wind a guard rail or bar *m* is extended outside of the supporting-posts and is secured thereto, so as to close the space between said posts, so that if the frame *d* is swung by the wind toward the posts *c* it will engage the guard-rail and be prevented from being swung between the posts *c*.

Provision is made for maintaining the frames stationary in an inclined position when said frames in their travel have reached a position where they are exposed to the sun. This result may be accomplished in a variety of ways, and in the present instance one arrangement is shown for this purpose. To this end a series of posts *n* may be employed, which are arranged substantially parallel with the support *a*, and each post *n* may be provided with a series of eyes *o*, arranged at different heights on the post, and the frame *d* may be provided with an eye *p*, which is adapted to be engaged by one end of a hook or locking device *r*, the other end of which is engaged with one of the eyes *o* on the post *n*. In this manner the frame may be arrested in its travel and also inclined or tilted on the rail *a* as a pivot, so as to better expose the skin to the action of the sun.

By engaging the hook *r* with an upper eye *o* on the post the frame may be brought into a position approximating the horizontal, as represented at the right in Fig. 1, and by engaging the hook *r* with one of the lower eyes the frame may be brought into a position approximating the vertical. In this manner the frames may be adjusted by the workman, if so desired, to conform to the position of the sun and obtain a more direct projection of the sun's rays upon the skin, thereby effecting a uniform drying of the skin in a minimum time.

Provision is made for locking or holding the frame to the rail *a* against accidental disengagement by the wind while in an inclined position, and this may be accomplished by providing the rail *a* with a recess, groove, or undercut portion forming a projection or lip 10 below the tread of the rail, with which the flange on the wheel *e* engages after the manner represented in Fig. 2.

The apparatus may be provided with two substantially parallel rails *a*, located at oppo-

site sides of the supporting-posts *c*, and the apparatus may be so positioned or arranged as to use one for the morning sun and the other for the afternoon sun, or both may be used at the same time.

In practice the apparatus herein shown may be arranged to extend from one building through an open space into another building, thence through another open space into a third building, &c., according to the 75 number of coats of enamel or other composition which is applied to the skin, and in this manner the skin attached to a frame is automatically conveyed from the place where the initial coat is applied to the skin to the place 80 where the finishing process is carried on, it only being necessary to provide attendants for arranging the frames for exposure to the sun in the open spaces referred to. It will also be observed that in case of a shower or 85 sudden rain the skins can be got under cover in the least possible time, as it would only be necessary to release the exposed frames from their inclined positions, whereupon the said frames would automatically start on their 90 journey to the building into which the support *a* gravitates, or the said frames may be quickly pushed back into the building from which they started. It will also be observed that the labor required to handle the frames 95 is reduced to a minimum, and a most efficient drying of the skins is effected in a minimum time.

One form of apparatus, which may be preferred, is herein shown; but it is not desired to limit the invention to the particular construction herein shown.

I claim—

1. In an apparatus of the class described, in combination, an elevated rail, uprights or posts to support said rail, a drying-frame to which a skin is secured, trolley-wheels carried by said frame and engaging said rail to support the said frame thereon, a guard-bar secured to said uprights or posts below the said rail to prevent said drying-frame from entering the space between adjacent posts and be thereby arrested in its travel on said rail, and means to render the said frame stationary on said rail and to secure the same in an inclined position with relation thereto, substantially as described.

2. In an apparatus of the class described, in combination, an elevated rail, uprights or posts to support said rail, a drying-frame to which a skin is secured, trolley-wheels carried by said frame and engaging said rail to support the said frame thereon, a guard-bar secured to said uprights or posts below the said rail, means on said rail to prevent said trolley-wheels being disengaged therefrom when said frame is in an inclined position, and means to secure the said frame in a stationary inclined position with relation to said rail, substantially as described.

3. In an apparatus of the class described, in combination, an elevated rail, means to support said rail in its elevated position, a drying-frame provided with means for engaging said rail to move thereon, and means to render said frame stationary on said rail and to secure the same in an inclined position with relation thereto, to adjust said frame and the skin thereon to different positions of the sun, substantially as described.

4. In an apparatus of the class described, in combination, a substantially continuous support, a drying-frame to which a skin is secured sustained by said support, and means to position said drying-frame on said support at an incline, substantially as described.

5. In an apparatus of the class described, in combination, an elevated rail, means to support said rail in its elevated position, a drying-frame provided with means for engaging said rail to move thereon, and means to secure said frame in different stationary inclined positions with relation to said rail, substantially as described.

6. In an apparatus of the class described, in combination, an elevated rail, uprights or posts to support said rail, a drying-frame to which a skin is secured, trolley-wheels carried by said frame and engaging said rail to support the said frame thereon, a guard extended longitudinally of said rail between said posts or uprights to prevent said frame engaging the same as the said frame is moved on said rail, substantially as described.

7. In an apparatus of the class described, in combination, an elevated rail, means to support said rail in its elevated position, a drying-frame suspended from said rail and movable thereon longitudinally and into a position inclined outwardly with relation to the path of longitudinal movement, and means to render said frame stationary on said rail and to secure it in an inclined position with relation thereto.

8. In an apparatus of the class described, in combination, a drying-frame to which a hide, skin or leather is secured, a support to sustain said frame while the latter is moved from one position to another, and means to render said frame stationary on said rail and to secure it in an inclined position while on said support, substantially as described.

9. In an apparatus of the class described, in combination, a drying-frame to which a hide, skin or leather is secured, an inclined support to sustain said frame while the latter is automatically moved by gravity from one position to another, and means coöoperating with said frame to render the same stationary on its support and hold the same in an inclined position with relation to said support, substantially as described.

In testimony whereof I have signed my name to this specification in the presence of two subscribing witnesses.

GEORGE W. HOLLIS.
